MANIFOLDING REGISTER

Carl W. Brenn, Montclair, N. J., assignor to
Autographic Register Company, Hoboken, N. J.,
a corporation of New Jersey

Application May 2, 1936, Serial No. 77,502

6 Claims. (Cl. 282—16)

This invention relates to manifolding registers.

Although the invention is not thus to be limited, it has primarily been made for, and is of particular value when embodied as, a small, lightweight, readily portable machine, that is, one which can be carried around easily, as by a salesperson or clerk frequently moving from place to place.

An object of the invention is to provide in a manifolding register, a new and improved record strip advancing mechanism characterized by simplicity of construction, reliability of operation and ease of manipulation.

Another object is to provide a novel and valuable starter means for the strip-advancing mechanism of a manifolding register.

Another object is to provide a register satisfying one or both of the objects foregoing, wherein also the record copies or slips can be stored in a record compartment while at the same time maintaining the size and weight of the register at a minimum.

Still another object is to provide such a register as that last described, and one wherein the record sheets are longitudinal subdivisions of a record strip wound on a roller in a record-receiving compartment, with such roller rotated in timed relation with, and participating to an advantageous extent in the operation of, the strip-advancing mechanism.

A further object is to provide a strip-feeding or advancing mechanism of the annular type but with the rotatory members thereof of very much smaller diameter than heretofore thought possible, yet able to advance a plurality of record strips simultaneously, and to repeat such advance a great number of times, each such advance being over a form-length along the strips, with only negligible disturbance of registry between the form-lengths of the different strips.

Another object is to provide, in connection with a strip-feeding mechanism of the annular type, and adapted when required for handling a plurality of strips which at form-length intervals therealong are provided with feed-arresting apertures, notches or equivalents, a novel and valuable means for arresting the feed of the strips when advanced a form-length.

Another object is to provide such an arresting means, and one which is of extreme simplicity yet readily releasable to allow the strips to be fed another form-length.

A further object is to provide an arresting and releasing means for the strip-advancing mechanism of extreme simplicity, yet one which need

be maintained in operative position only for that portion of an instant required to start the strip-advancing mechanism at the initiation of a form-feeding operation thereof.

Other features and advantages will hereinafter appear.

In the accompanying drawings which show a practical embodiment of the invention, and one now preferred.

Figure 1, in full lines, shows such register closed and locked and ready for use.

Fig. 2 shows the same in side elevation.

Fig. 3 is a top plan view of said register, with the top cover and the platen and associated parts removed, and with certain parts shown in section.

Fig. 4 is a vertical longitudinal section, with the top cover in place and there locked, and showing also the platen and its associated parts.

Fig. 5 is a detail elevational view, looking in the direction of the arrow 5 in Fig. 3 and also in the direction of the arrow 5 in Fig. 6.

Fig. 6 shows the parts of Fig. 5, but in horizontal section.

Fig. 7 is a detail elevational view of the parts behind the vertical plane 7—7 of Fig. 6.

Fig. 8 is a transverse vertical sectional view, taken through the closed casing on the line 8—8 of Fig. 3.

Fig. 9 is a fragmentary view illustrating more clearly certain details of construction, this view showing the parts incorporating these details as said parts are seen in Fig. 8.

The register of the present invention, in the exemplifying embodiment thereof illustrated in the drawings, is shown as having a casing 10, within which is a platen 11, and the top of which is adapted to be closed by a cover 12 hinged to the casing at 13. This cover incorporates a marginal frame for the platen, such frame surrounding a writing opening 14 overlying the platen and for exposing therethrough a sheet or form-length subdivision (marked 16a in Figure 1) of the uppermost one of a plurality of record strips. Three of such strips are shown in Fig. 4, marked respectively 16, 17 and 18.

Cover 12, conventionally, includes a portion constituting a hand-rest 12a, and the cover is also shown shaped so as to incorporate a hood 12b for housing a certain strip-overlying rotary subdivision of the strip-advancing mechanism, and so as to present beyond such hood in the direction of strip-feed a tear-off edge or knife 12k; such knife roofing over an exit opening 19 for the sheets carried by all the record strips.

employed, as the strips 16, 17 and 18, which are to be severed and distributed. As is understood in the art, all the sheets making up a matching set of form-length subdivisions of all the record sheets employed are advanced from their previously halted position over the platen 11, after these have been inscribed while so halted by operation of the strip-advancing mechanism which advances all the strips simultaneously a form-length extent; and when the strips to be severed are thereby issued from the machine through opening 19, usually a perforated or other weakened or otherwise predetermined tear-off line on each of the strips is brought below the knife 12k, while the lowermost sheet, that one forming part of the strip 18, is deflected within the machine for entry into a suitable storage compartment, here a compartment 20. As is also understood in the art, each mating set of sheets on all the record strips, while such set is at rest on the platen, are simultaneously similarly inscribed by the use of suitable duplicating or manifolding instrumentalities; these last being here shown, as indicated in Figure 4, as comprising carbon sheets 21, held in place according to principles well known in the art. These strips are free at their left-hand ends and also along their sides as far as their right-hand marginal portions, where they are secured to holding bars having opposite ends secured to points on the platen beyond the opposite side edges of the record strips by way of a plurality of hooks one of which is shown at 23.

Below the platen 11 the casing 10 is shown as incorporating a supply compartment 24 for a zigzag folded pad or stack of record strips; in the making of which pad, according to a practice now known in the art, the strips are superposed before the zigzag folding so that the sheets appropriate to a set thereof are properly interleaved incidental to such folding.

This compartment, at one side thereof, terminates in a partition-plate 25, having an inwardly and downwardly extending struck-outleaf or tongue 25a for engaging a side of said pad or stack, as indicated at 25' in Figure 1, and for serving other purposes, as will hereinafter appear.

At 26 (Fig. 4) is shown, partially broken away, one of a pair of plate-hangers, suitably secured to the platen 11, and mounting between them a roller 27 over which the record strips 16, 17 and 18 are guided for passage onto the receiving end 11a of the platen, as successive sets of sheets are drawn from the top of the zigzag folded pad or stack.

Like the cover 12, the platen 11 is hinged at one side to a side wall of the casing, at 13; that is, side wall of the casing marked 10a in Fig. 2, and also the platen and the cover, are each provided with a line of offset and spaced extensions curled into hinge-collars all taking a common pintle-rod 28. One of such collars of each of the casing, of the platen and of the cover, are marked in Fig. 2, respectively, 10c, 11c and 12c. When the platen is lowered as shown in Fig. 4, the side thereof opposite its hinged side, rests on a shelf 11d slightly above a horizontal flange at the top of partition-plate 25, such flange being marked 25b in Fig. 3. When the cover 12 is thereafter lowered as shown in Figure 1, the side thereof opposite its hinged side rests on the top edge of the side wall of the casing adjacent to said partition-plate.

When the cover 12 is lowered, the part 12a

thereof coacts with the tops of the carbon-hanging hooks 23 to hold the platen against other than negligible displacement from its position as shown in Fig. 4, even when the machine is turned upside-down. When the machine is in working position, that is, is arranged upright and substantially horizontal, the platen by its own weight comes properly to rest on the shelf 11d.

Referring to Figs. 3 and 4, a locking means for the cover is shown as including a rib-like projection 29, offset from the far side of the plate-hanger 26 seen in Fig. 4, and a seizing keeper or hook 30a formed at one side of an opening 30b in a shift-bar or bolt 30. This bolt, between partition-plate 25 and the adjacent side wall of the casing, is guided in its endwise shiftings between a widened terminal part 25b' (Fig. 3) of flange 25b and a pair of ribs 31 suitably fixed in place (Fig. 4). The lock is preferably double acting; that is, the bolt is provided with two hooks and projections to be seized by the hooks—such additional hook and projection being indicated in Fig. 3 at 29' and 30a' respectively.

As the bolt 30 is shown in Fig. 4, the cover is locked closed. When, however, such bolt is shifted to the right, hook 30a is disengaged from the projection 29, the opening 30b being wide enough to allow this, and the cover is unlocked. Such unlocking is accomplished by applying the proper key (not shown) to a key hole 32' in a lock barrel 32 in a lock-case 33; said barrel being rotatable by the proper key about its pivot 32a and carrying an eccentric 32b fitting in an opening 30c in the bolt. Thus, on turning the barrel in one direction or the other, the bolt is shifted toward the right or toward the left in Fig. 4, in the first case to unlock the cover 12, and in the second case to lock such cover.

It will be noted that it is the lock-case 33 which at its top surface provides the aforesaid shelf 11d on which platen 11 rests by gravity during operation of the machine.

When the cover is closed and locked, it closes and also locks a curvilinear auxiliary end-cover 34 when the last-mentioned cover has been previously closed. This cover 34, hinged at 35 to the casing sides, is openable as shown in Fig. 4, but is seen in locked condition in Figures 1 and 2, a terminal lip thereof, marked 34a in Fig. 3, being then caught under the flat end-portion of the cover 12 adjacent the knife 12k and being positively so held by the engagement of a stud 12e (Figure 1) downwardly projected from the underside of cover 12 so as to enter an accommodating properly placed aperture in said lip 34a.

When the cover 34 is opened, access is had to the interior of the record compartment 20, to thread the leading end of a leading sheet on the lowermost record strip into a gripper carried by a wind-up roller 36, and to remove the strip previously wound thereon. Referring in this connection to Figs. 3 and 4, said roller is shown as of square cross-section and carrying a strip 37 L-shaped in cross-section. One of the two leaves making up this strip is shown vertically disposed in Fig. 4, and this leaf is suitably made fast to a flat face of a roller 36, so that the other leaf of the strip, outwardly lipped at its free edge, snugly facewisely engages another flat face of the roller. Such face engagement of these parts, when the last-mentioned leaf is resiliently urged against the roller, as is preferably accomplished by providing strip 37 of thin spring metal, affords a

convenient means for securely attaching the leading end of a record strip to the roller, so that on turning of the latter in an anti-clockwise direction as seen in Fig. 4, such strip can be wound up tightly on the roller.

The journalling means for the roller includes at one end of the latter a recess 38 taking a trunnion 39a; the roller at its other end carrying a small pointed stud 40 seated in a hole 41 in a plate 42 secured to a side wall of the casing.

In order to remove the roller from its journalling mounts, the following parts are provided. The roller has a cylindrical chamber 36a at its end adjacent to the stud 40, said stud being at the outer end of a stem 43 carrying a cylindrical plunger 43' in said chamber. The plunger is urged to protrusion by an expansile coil spring 44 in chamber 36a and surrounding the stem 43 guided in a bore 36b coaxial with chamber 36a; but said plunger is restrained to telescopic integrity with roller 36 by a pin-and-slot connection 46. Plate 42 in its side facing the interior of the record compartment 20, is slotted as indicated at 47, this slot terminating at the hole 41.

To demount the roller 36, as to remove a record strip wound thereon, said roller is moved end-wisely to telescope over plunger 43, whereupon the roller can be swung laterally to clear its end-carrying recess 38 from trunnion 39. To remount the roller, it is cantwisely inserted to cause its recess 38 angularly to engage the trunnion, and the pin 40 is then entered into the groove 47 and pushed along said groove until it snaps into the hole 41.

When so mounted the roller 36 is rotated with a spur gear 48, by a friction connection including a rubber washer 49 between said gear and the flange illustrated on the adjacent end of the roller; such washer being somewhat compressed by the end thrust of such flange, due to the action of the spring 45, when the roller is in place.

Trunnion 39a is part (Figs. 5 and 6) of a stub-shaft 39 having a central smooth part journaled in a pair of matching apertures in a side wall of the casing 10 and in a plate 50 riveted to said wall as indicated at 51 in Fig. 3. Stub-shaft 39 is shown in Fig. 6 as provided with straight knurlings whereby gear 48 and a ratchet 52 may be made fast thereon by forced fit. Said ratchet is on the outside of the side wall last-mentioned, but within a cup-like box 53 within which is mounted a pawl 54 (Fig. 7) for the ratchet and a leaf spring 55 for urging the pawl toward engagement with the teeth of the ratchet. Box 53 is provided with a central opening having a loose fit around the hub of ratchet 52, and is secured in place by screws 56. Thus the gear 48 and roller 36 can be freely rotated in an anti-clockwise direction as viewed in Fig. 4, but never in the reverse direction, because of the ratchet and pawl just described.

The means for thus rotating said gear and roller is here shown as comprising a hand-crank means of collapsible type; this means including an arm 57 pivotally mounted at 58 and carrying at its free end a handle or knob 59. Said arm is thus pivoted to a pair of ears 60a upstanding from a plate 60 held against but rotatable relative to the outer surface of box 53. A nut 61 is applied to a threaded end-length 39b of stub-shaft 39; this nut being so shouldered, such shoulder being shown in Fig. 6, as not only to mount plate 60 as just above described, but also so as to be free of engagement with the hub portion of ratchet 52. Above such shoulder, the nut

61 is square, and beyond its square formation, it is shaped like the frustum of a cone, so that when the arm 57 is swung from its collapsed position, shown in full lines in Figures 1 and 3 and in broken lines in Fig. 2, to the position shown in dot-and-dash lines in Fig. 2, which is its operating position, a square opening 57a therein keys the arm to the square portion of nut 61. A spring 62 is provided normally to urge the arm 57 away from its position and keyed to nut as just explained. When, however, arm 57 is in its collapsed position, it is frictionally held in that position, as then the knob 59 is partially entered into the casing through a suitable aperture in the adjacent side wall thereof for frictional seizure by the matchingly shaped portions 63a of a leaf spring 63 otherwise of hairpin shape held in an accommodately formed pocket 64 in a plate, not shown, suitably secured to a partition-plate 25 below the latter's top flange 25b. While the arm 57 is thus held in collapsed position, the crown of the knob 59 lies against the leaf 25a and is partitioned off by the latter from the record-strip contents of the supply compartment 24.

Referring to the strip-advancing means shown, this includes a strip-underlying annular member in the form of a roller 66 and strip-overlying annular member in the form of a roller 65. During strip feeding, the roller 65 turns in a clockwise direction and the roller 66 in a counterclockwise direction as these rollers are seen in Fig. 4, simultaneously with rotation of the roller 36 as above described, that is, in a counterclockwise direction. A spur gear which turns with the last-mentioned roller meshes with a spur gear 67 (Fig. 4), and this gear 67 meshes with a spur gear 68 (Fig. 8) fixed on a shaft 69 on which is secured roller 66. Gear 68 meshes with a spur gear 70 (Figs. 4 and 8) fixed on a shaft 71 on which is secured roller 65. As indicated in Fig. 8, shaft 69 is journaled in side plates suitably fixed in the casing 10, and shaft 71 is journaled in side plates suitably fixed in the cover 12.

Thus, when the cover is opened, the roller 65 is bodily lifted away from the roller 66.

The rollers 65 and 66 are shown as interrupted at points along their lengths, each roller being thereby divided into a longer central portion and shorter terminal portions, these last for engaging the strips along side margins thereof and the longer central roller lengths for engaging the strips at the main central portions thereof.

As shown, one of the rollers, here the upper roller 65, has a knurled working surface, this roller being preferably of metal. As the invention is now understood, one of the two rollers 65 and 66 should be considerably softer than the other. In the present case, the lower roller 66 is of soft rubber. Then, with the roller shafts spaced apart, as they are in the embodiment of the invention now being described, somewhat less than the sum of the radii of the two rollers when the rubber roller is free from any deforming constraint, the rubber roller 66 is compressed by the harder roller 65 along the line of contact between the two rollers in such manner that this contact is not a mere line one but is of appreciable if not considerable width; the rubber roller being bulged laterally to a noticeable extent in the actual operating machine. Such bulging may have, and probably has, considerable to do with the true explanation of why said machine in practice operates with such high efficiency so far as is concerned its action in advancing to tear-off posi-

tion a large number of successive form-length subdivisions of a plurality of record strips without having one or more of these strips longitudinally creep relative to other or others thereof and consequently without causing their form-registering apertures, notches or equivalent elements to lose registration.

Referring to Figure 1, a plurality of the elements last referred to, here in the form of apertures of a familiar type, are indicated at 72.

These apertures are provided for the purpose of arresting all the strips simultaneously at the conclusion of each form-feeding advance thereof.

The strip-arresting means here shown, and the means here shown which releases the latter when the strips are again to be advanced a form-length extent, will now be described.

Extended within the spacings between the major and minor subdivisions of the rollers 65 and 66, are upstanding hooks 73 at the ends of fingers 74 horizontally extended from the top of a plate 75 supported flatwise against a vertical transverse wall 76 having at its lower edge a flange 76a secured to the bottom of the casing as indicated at 77 in Fig. 3. Plate 75 is bodily movable in an up and down direction relative to wall 76, because held slidably thereagainst by rivets 78 the shanks of which not only pass through suitable apertures in said wall but also act as the pin elements of two pin-and-slot connections between said plate and wall the slots whereof are formed in the plate. These slots, near opposite ends of said plate, are seen at 79 in Fig. 8, one of them being very clearly shown in Fig. 9. A V-shaped leaf spring 80 centrally secured by a screw 81, and having end portions similarly resiliently acting in an upward direction on fingers 74, urges plate 75 toward its elevated position and in such manner as always to hold said plate against canting from the horizontal in any position thereof and during up and down movements thereof.

When the plate 75 is elevated, the hooks 73 are in position to enter the apertures 72 of a mating set of sheets carried by the record strips, so as to engage said sheets as soon as they, in course of advancement, have been fed forward far enough to bring under the knife 12k the tear-off lines of those of said sheets which are to be severed and distributed.

In order, when said engagement occurs, to lock the rollers 65 and 66 against further rotation in strip-advancing direction, a ratchet 82 is fixed on the shaft 69 on which is secured the roller 66; and the instant the hook 73 enters the apertures 72 of a mating set of sheets carried by the record strips, the plate 75 is elevated to the position shown in the drawings, thus raising a leaf-spring pawl 83, carried by the plate, to the illustrated engagement with ratchet 82.

However, during that part of any strip advancement which follows an initial forward feeding of the form-lengths then to be advanced sufficiently to pass the apertures 72 beyond the hooks 73, once these hooks have been held lowered during said initial feeding, by the means described in the paragraph next below, the solid portions of the strips thus brought over the upper ends of the hooks (which ends are smoothly blunt) exert a downward pressure on these hooks

great enough to overbear the relatively light tension of the spring 80. Consequently, the plate 75 is maintained depressed, thereby holding the pawl 83 away from the ratchet 82. It will be noted in this connection that the hooks 73 are here shown as located substantially in vertical

alignment with the axes of rotation of the rollers 65 and 66. Due to the downward pressure from the solid portions of the strips, once the plate has been thus depressed it will be so maintained until, as the result of strip-advancing rotations of the rollers 65 and 66, apertures corresponding to the apertures 72, and carried by a following set of sheets on the record strips, pass over and engage the hooks 73, thereby to arrest strip advancement as above described.

In order manually to release the strip-arresting hooks 73, for the initiation of a strip advancement, means is shown which includes a finger-piece 84 at the side of the machine opposite to that carrying the operating arm or handle 57. This finger-piece is fixed on a transverse rock-shaft 85, suitably journaled near opposite sides of the casing, and having fixed thereon sleeve 86 carrying a pair of curved claws 87 (Figs. 3 and 8) each extending through a slot in the wall 76 and through an opening in plate 75, as shown perhaps most clearly in Fig. 4, where the slot there illustrated is marked 88.

Operation

The handle 57 being set in the operating position shown in dot-and-dash lines in Figure 1, when it is desired to advance the strips a form-length extent the finger-piece 84 is rocked in the direction indicated by the arrow 84a in Fig. 4. Thereby, the claws 87 are swung down. This lowers the hooks 73 below the apertures 72 when engaged by said hooks, and also clears the pawl 83 away from the ratchet 82.

While the finger-piece is momentarily held thus out of its normal position, as by a slight thrust by the middle finger of one hand, the handle 57 is turned by the other hand that slight amount sufficient to advance the strips to pass the apertures last-mentioned beyond the hooks.

Said finger-piece may now be released, as the solid portion of the record strips now over the hooks 73 maintain the ratchet 82 and pawl 83 out of engagement.

From this point on it is merely necessary to turn the handle 57 in the same direction as before—a counterclockwise one, as such handle is seen in Fig. 2. During such rotation of the handle, the rollers 65 and 66 are rotated, and while they coast to effect strip advancement, the roller 36 is simultaneously turned in the proper direction to wind-up thereon the sheet of the lowermost record strip corresponding to the sheets of the overlying record strips which are being advanced passed the knife 12k.

As soon as the tear-off lines of the sheets last-mentioned arrived under side knife, the apertures 72 of the follower set of sheets on the record strips arrive over the hooks 73, the spring 80 elevates the plate 75, and the pawl 82 again engages the ratchet 83, locking the handle 57 against further rotation.

Due to the gearing together as already explained of the rollers 36, 65 and 66, and to the ratchet pawl means of Fig. 7 associated with the roller 36, the strip-advancing mechanism can at no time be operated in the direction opposite to that required for strip advancement.

During portage of the machine, or otherwise when convenient, handle 57 is collapsed as shown in Fig. 3, and then the length of the register is made even shorter than the over-all unusually short length thereof made possible by the employment of a wind-up roller in the record com-

partment and by the fact that the strip-advancing mechanism of the present invention avoids the previous necessity of having at least one of the strip-underlying and strip-overlying annular strip-engaging means, said means here shown as comprising the rollers 65 and 66 of comparatively large diameter as compared to the diameter of the other. Also, due to the fact that the arm 57 is normally urged by the spring 62 toward the col-

10 lapsed position shown in Fig. 3, there is never any chance that accidental or casual rotation of said arm will inadvertently cause strip advancement, even when at the instant of such casual movement finger-piece 84 is accidentally kicked over in the direction shown by the arrow 84a in Fig. 4.

Variations and modifications may be made within the scope of this invention, and portions of the improvements may be used without others.

20 I claim:

1. In a manifolding machine for record strips having cut-away portions at form-length intervals therealong with all said cut-away portions in line along the strip to define a band-portion 25 of the strip running longitudinally thereof, a strip-advancing means comprising solely a strip-overlying roller and a strip-underlying roller; a manual actuator for said rollers; mounting means for said rollers for maintaining them 30 constantly in strip-advancing adjacency during and between successive strip advancements, said rollers being so shaped that they are constantly out of engagement with said band-portion of the strip; a strip-arresting means including a detent 35 for engaging a cut-away portion of a strip at the completion of an operation of said strip-advancing means to advance a strip a sufficient amount to bring a cut-away portion of the strip to a location approximately vertically below the

axis of the upper roller; and a second manual actuator for freeing the detent from its said engagement during initial operation of the first-mentioned manual actuator while the latter is operating the strip-advancing means.

2. A manifolding machine as in claim 1, where-
in there is a means for yieldably urging said detent member toward engagement with said portion.

3. A manifolding machine as in claim 1, where-
in there is a means for yieldably urging said detent member toward engagement with said portion; and there is also a means including said rollers for maintaining said detent member ineffective following a strip advance sufficient to move said portion beyond said location, the means last-mentioned also including the corpus 10 of the record strip.

4. A manifolding machine as in claim 1, where-
in there is a means for locking said advancing 20 means against further strip-advancing operation when said detent engages said cut-away portion.

5. A manifolding machine as in claim 1, where-
in there are provided a means for locking said advancing means against further strip-advancing 25 operation when said detent engages said cut-away portion; means including said rollers for maintaining said detent member ineffective; and means for rendering said locking means ineffective, both the means last-mentioned acting when 30 a record strip advance is effected sufficient to move said cut-away portion beyond said location.

6. A manifolding machine as in claim 1, where-
in there is a means for yieldably urging said detent member toward engagement with said 35 cut-away portion, the paper upon being moved by the rollers acting to maintain said detent free during operation of the first-mentioned actuator.

CARL W. BRENN.
